[57] CLAIM

The ornamental design for a welding-wire guide for arc coating devices, as shown and described.

DESCRIPTION

FIG. 1 is a perspective view of the welding-wire guide for arc coating devices of the present invention;

FIG. 2 is a side plan view of the welding-wire guide for arc coating devices of the present invention;

FIG. 3 is an end view from one end of the welding-wire guide for arc coating devices of the present invention;

FIG. 4 is an end view of the opposite end of the welding-wire guide for arc coating devices of the present invention; and,

FIG. 5 is a side elevational view of the welding-wire guide for arc coating devices of the present invention.
